Inventor:
Walker Evans.
By Wright & Port Atty's.

No. 36,358.

Patented June 9, 1903.

UNITED STATES PATENT OFFICE.

WALKER EVANS, OF ST. LOUIS, MISSOURI.

DESIGN FOR A FONT OF TYPE.

SPECIFICATION forming part of Design No. 36,358, dated June 9, 1903.

Application filed April 25, 1903. Serial No. 154,368. Term of patent 14 years.

To all whom it may concern:

Be it known that I, WALKER EVANS, a citizen of the United States, residing in the city of St. Louis, in the State of Missouri, have invented and produced a new and original ornamental Design for Fonts of Type, of which the following is a full, clear, and exact description, reference being had to the accompanying drawing, forming part of this specification.

The drawing illustrates a face view of my font of type.

I claim as my invention—

The ornamental design for a font of type herein shown.

WALKER EVANS.

In presence of—

E. S. KNIGHT,
BLANCHE HOGAN.
